UNITED STATES PATENT OFFICE.

CATHARINE A. GRISWOLD, OF NEW YORK, N. Y.

DESIGN FOR THE ORNAMENTATION OF CORSETS.

SPECIFICATION forming part of Design No. 19,236, dated July 30, 1889.

Application filed June 29, 1889. Serial No. 316,096. Term of patent 14 years.

To all whom it may concern:

Be it known that I, CATHARINE A. GRISWOLD, of the city, county, and State of New York, a citizen of the United States, have 5 invented and produced a new and original Design for the Ornamentation of Corsets, of which the following is a full, clear, and exact description, reference being had to the accompanying drawing, forming part of this specification.

The single figure in the drawing represents in side elevation a corset containing my invention.

The leading and special feature of my new 15 design consists in a band or stripe which is curved or bent upon itself about midway its ends, and said ends of which are approximately rectilinear in direction and converge toward each other at their free extremities, 20 said band or stripe thus shaped extending at about the waist-line of the corset longitudinally upwardly and downwardly across the waist-line.

A represents a corset, which may be in the 25 usual and ordinary form.

B represents a band or stripe, which has

the curve or bend b upon itself at about midway its ends, and said ends b' and b'' of which are approximately rectilinear in direction and converge toward each other at their free extremities, as shown. This band or stripe thus shaped extends at or about the waist-line of the corset longitudinally upwardly and downwardly of the corset across said waist-line, as shown.

35

What I claim is—

The design for the ornamentation of a corset herein described and shown, the same consisting in a band or stripe B, which has the curve or bend b upon itself about midway its 40 ends, and said ends b' and b'' of which are approximately rectilinear in direction and converge toward each other at their free extremities, said band or stripe extending at or about the waist-line of the corset longitudinally 45 upwardly and downwardly of the corset across said waist-line.

CATHARINE A. GRISWOLD.
